(57) CLAIM

The ornamental design for a miniature attache case, as shown and described.

DESCRIPTION

FIG. 1 is a perspective view of the miniature attache case showing my new design;

FIG. 2 is a top view thereof;

FIG. 3 is a front elevational view thereof;

FIG. 4 is a right side view thereof;

FIG. 5 is a bottom view thereof; and,

FIG. 6 is a plan view of the miniature attache case of FIG.
1 in an unfolded condition.

The present application is directed to the design illustrated in the drawings. The broken line portions of the disclosure are for illustrative purposes only and form no part of the claimed design.
